Charles F. Bauer, Rte. 1, Box 330,
Barrington, Ill. 60010

Filed Oct. 22, 1965, Ser. No. 87,809

Term of patent 14 Years

(Cl. D15—1)

FIG. 1 is a perspective view of a sling chair showing my new design;

FIG. 2 is a side elevational view thereof;

FIG. 3 is a front elevational view thereof;

FIG. 4 is a rear elevational view thereof;

FIG. 5 is a top plan view thereof; and

In FIGS. 2-5 the broken line showing of the sling portion has been omitted for convenience of illustration.

An elevational view showing the side opposite to that shown in FIG. 2 is the same as FIG. 2.

The dominant features of the design reside in the portion shown in full lines.

I claim:

The ornamental design for a sling chair substantially as shown and described.
